[57] ABSTRACT

A device for use on an offset lithographic printing press, having a plate cylinder and a water cylinder from which water from a cooperable supply is to be transferred to the plate cylinder, to control the amount of water on the water cylinder, comprising a plurality of pliable rubber-like members disposed in a row in side-by-side relation and arranged to engage the face of the water cylinder substantially throughout its operative length and provided with manually adjustable means whereby the squeegee action of the respective members may be individually determined to effect a desired control of the amount of water on the face of the cylinder, the device readily being constructed for attachment to existing presses, as well as incorporated in new presses.

8 Claims, 2 Drawing Figures

WATER CONTROL DEVICE FOR OFFSET LITHOGRAPHIC PRINTING PRESSES

BACKGROUND OF THE INVENTION

The invention is directed to apparatus which may be attached to or incorporated in an offset lithographic press for controlling the application of water to the printing cylinder prior to the reception of the printing ink thereon.

It is particularly desirable in presses of this type that the moisture transferred to the printing cylinder be substantially uniformly applied whereby spotting with insufficient or too much water is prevented.

Various types of so-called water checks, or squeegee devices, have been employed with the water cylinder of such a press which involved, for example, disposition of a suitable member extending continuously along the water roller in axial direction and bearing on the surface of the cylinder for removing excess water therefrom.

However, oftentimes the surface of the water cylinder may have an area or areas which has picked up oil or greasy material, for example possibly from the ink employed, whereby such area or areas will not pick up water to the same extent as that of the remaining area of the cylinder. In many cases, it has been found necessary to stop the press and clean the cylinder surface in order to eliminate the problem. Where a continuous or substantially continuous structure is employed, such cleaning operation is normally the only solution to the problem as there is no way in which a selective control of the amount of water on the cylinder may be achieved.

The present invention thus is directed to the solution to this problem, enabling the press operator to readily compensate for surface variations on the water cylinder without stopping the press or effecting a cleaning operation on the cylinder.

BRIEF SUMMARY OF THE INVENTION

The desired results are achieved in the present invention by providing a structure in which of the amount of water on the water cylinder may be selectively and adjustably controlled at a plurality of points along the cylinder surface, whereby special very fine, micrometer-type adjustment may be effected at any desired location to compensate for specific conditions thereat.

The structure of the invention comprises a plurality of individually controllable more or less resilient sheet-like members having free edges which may bear upon the surface of the water cylinder to provide a squeegee action thereon with respect to excess water on the face of the cylinder. Each of the individual members may be independently adjusted as to its bearing pressure on the cylinder whereby the amount of water retained on the cylinder may be selectively and independently adjusted along the entire face of the cylinder.

The mounting of the structure may vary with the press construction, and in the embodiment the invention illustrated, each of the resilient squeegee members are supported from a longitudinally extending supporting bar by means of respective resilient metallic elements, each of which is firmly connected to the supporting bar at one end and carries the resilient squeegee member at the opposite end thereof. Suitable means is provided for effecting in simple manner a manual adjustment by means of which pressure may be

exerted on the individual squeegee members to control the pressure exerted thereby on the surface of the cylinder. In the embodiment the invention illustrated, such adjusting means comprises a knob having a threaded stem which is threaded into a part of the supporting structure whereby tension may be applied, to the squeegee assembly or relieved therefrom by rotating the knob in appropriate direction.

The press operator thus may readily finely and accurately adjust the respective squeegee members, while the press is in operation, merely by rotating the desired knob or knobs in directions adapted to provide the desired action, either increasing or decreasing the pressure of the resilient members on the surface of the water cylinder and thus the amount of water thereon.

Means are also provided for mounting the control device on the press structure, for example on the edge of the water supply tray associated with the water cylinder, with the control device readily being adapted to be constructed as an attachment to existing presses, whereby the advantages of the present invention may be achieved with older presses.

The control device preferably is constructed of materials having high resistance to any materials with which they may come in contact, the resilient squeegee member preferably being fabricated from a resilient synthetic or natural rubber and the resilient connecting elements being constructed from stainless steel or the like.

BRIEF DESCRIPTION OF THE DRAWINGS

In the drawings, wherein like reference characters indicate like or corresponding parts,

FIG. 1 is a sectional view through a controlled device illustrated in accordance with the present invention, taken approximately on the line I—I of FIG. 2; and

FIG. 2 is a top plan view of a portion of the control structure per se, illustrated in FIG. 1.

DETAILED DESCRIPTION OF THE INVENTION

Referring to the drawings, the reference numeral 1 indicates generally a control device constructed in accordance with the present invention, disposed adjacent a water cylinder 2 of an offset lithographic press and supported from the water supply tray 3 thereof.

The control device 1 comprises an elongated base or supporting member 4, which is generally L-shaped in transverse cross-section and thus may comprise a standard angle member. Carried by the member 4 are a plurality of resilient members 5, constructed, for example, from synthetic or natural rubber or the like having a free edge 6 adapted to bear on the adjacent face of the water cylinder 2, with the respective members 5 each being supported from the member 4 by means of a thin metal element or strip 7, which preferably is of spring stainless steel or the like, with the member 5 being secured to the element 7 by a relatively large headed screw 8 extending through the adjacent portions of the members 5 and 7 and secured in position by a nut 9 bearing on a washer 10.

The opposite end of each spring strip 7 is provided with a mounting portion 11 extending at right angle to the main body of the strip 7 and secured to the adjacent wall 12 of the member 4 by means of a screw 13 and angle member 14, with the portion 11 of the strip 7 thereby being clamped between the wall 12 and adjacent wall 15 of the angle member. As will be apparent from reference to FIG. 2, each strip 7 preferably is

secured to the member 4 by a respective individual angle member 14 and screw 13, thereby enabling replacement of each member 7 independently of the remaining members thereof. Threaded in the outwardly extending wall 16 of each of the angle members 14 is a screw 17, the free-end of which extends through an opening in the associated strip 7 and terminates in a knob 18 rigidly secured to the screw, by means of which the screw may be rotated in the wall 16. Thus, by suitable rotation of the knob 18 and thereby the screw 17, the knob 18 may be moved to apply pressure to the strip 7 and thus to the resilient member 5 for control of the pressure applied by the free edge 6 of the member 5 to the surface of the water cylinder 2.

Support member 4 preferably is so positioned that when the knob 18 applies no pressure to the strip 7 the member 5 will just be out of engagement with the surface of the cylinder 2 and by rotating the knob 18 in a clockwise direction the knob will be moved downwardly applying pressure to the strip 7 and thus effecting engagement of the edge 6 with the surface of the water cylinder, with the amount of pressure thereon being determined by the adjustment of the knob 18.

The member 4 is adapted to be connected with the tray 3 by a plurality of metal strips 19, secured by screws 20 to the member 4. The number of strips will normally be determined by the length of the cylinder 2, with at least one strip being disposed adjacent each end of the member 4 and as many intermediate strips as it is deemed desirable to provide adequate connection of the member 4. The opposite ends of each strip 19 is secured to a corresponding block 21 by means of one or more screws 22 extending through the adjacent end of the strip and threaded into the block. As clearly illustrated in FIG. 1, the block 21 is provided with a slot 22 therein of a size to receive the upper edge of the adjacent side wall 24 of the water supply tray 3 and clamped in operative position therein by means of a screw 25. The supporting member 4 is additionally retained in operative position by a plurality of like members 26, for example disposed adjacent each end of the member 4 and if necessary or desirable with one or more intermediate members being disposed at space intervals therebetween. Each member 26 is adapted to be threaded into an adjacent bracket member 14 and locked in position with respect thereto by means of a lock nut 27. The structure thus is suitably supported independently of engagement of the members 5 with the water cylinder.

In use each of the members 5 may be suitably adjusted in a normal position providing a relatively uniform desired amount of water on the surface of the cylinder 2. Any desired adjustment may then be effected anywhere along the cylinder by rotation of the appropriate knob 18 for the member 5 bearing on the area of the cylinder involved, so that the amount of water at such area may be increased or decreased by proper rotation of the knob 18. The screw adjustment provided for each of the individual members 5 thus enable a very fine micrometer adjustment of the pressure of the associated member on the surface of the cylinder to provide the desired adjustment of the amount of water remaining on the cylinder. If, during operation of the press, the surface characteristics of the cylinder should change, the operator can readily compensate therefor, at the area involved, by appropriate adjustment.

Replacement of any of the members 5 may be readily achieved by removal of the nut 9 and washer 10 associated therewith, permitting removal of the associated member and replacement with a new member. The strips 7, as previously mentioned, may be readily fabricated from stainless steel and the use of stainless steel screws 8, nuts 9 and washers 10, together with resilient members 5 of synthetic rubber or the like, results in a very durable structure which is relatively unfeasted by any of the materials which would normally come in contact therewith. The supporting structure, comprising members 4 and 14, may be fabricated of any suitable material, such as stainless steel or brass, stainless steel being found to be very effective therefor, and in like manner the mounting strips 19, legs 26 and block 21 may be fabricated of brass, stainless steel or other suitable material.

It will be apparent that the width of the members 5 may be varied in dependence upon the specific application, with a width of from $\frac{1}{8}$ to $1\frac{1}{8}$ inches being deemed suitable for most applications. The knobs 18 may be of any suitable material, as for example a suitable plastic and firmly threaded down on the free end of each screw to provide a rigid connection therebetween, with the head of the associated screw forming limiting means for the screw and preventing the unscrewing thereof from the associated bracket 14.

It will be appreciated from the above description that I have provided a relatively very simple construction and yet highly efficient for the purposes intended which may be readily constructed as an attachment for existing presses as well as being incorporated in the design of new presses.

Having thus described my invention it will be obvious that although various minor modifications might be suggested by those versed in the art, it should be understood that I wish to embody within the scope of the patent granted hereon all such modifications as reasonably, and properly come within the scope of my contribution to the art.

I claim as my invention:

1. A control device for the water cylinder of an offset lithographic printing press, having a plate cylinder and a water cylinder from which water from a cooperable supply is to be transferred to the plate cylinder, comprising an elongated support structure having an upper leg and a lower leg connected by an intermediate portion of generally U-shape in transverse cross-section, adapted to be disposed laterally adjacent such a water cylinder at the side thereof exiting from such a supply, the upper leg of said U-shaped support structure being of less length, in transverse cross section, than the lower leg thereof, with the open end of said U-shaped configuration facing such cylinder, a plurality of resilient strip-like metallic elements, each having a corresponding end disposed in a common plane and mounted on the intermediate portion of said support structure, with such elements extending in generally parallel relation toward said cylinder but spaced therefrom, a plurality of cylinder-engaging members, each carried by a respective resilient element at the opposite free end thereof, said members being formed from a pliable rubber-like material and disposed in a row in substantially side-by-side relation and having their outer edges in substantially aligned relation for engagement with the surface of such a water cylinder substantially throughout its operative length, to effect a squeegee action with respect to water disposed on the face

thereof, a manually actuatable screw for each resilient element and cooperable member, extending through the associated element and threaded into the lower leg of said support structure, each screw including a manually actuatable knob rigidly connected thereto, by means of which the screw may be rotated, each knob being adapted to apply pressure on the upper face of the associated resilient element for flexing the same to control the pressure of the associated resilient member on the surface of the cylinder and thereby control the amount of water thereafter retained on the cylinder and thus ultimately transferred therefrom to the plate cylinder of such a press.

2. A control device according to claim 1, wherein each of said screws is threaded into the lower leg of said U-shaped structure and provided with a head at the opposite end thereof from the knob carried thereby, with such head disposed at the bottom side of said lower leg, whereby the knob and screw assembly cannot be turned out of the same.

3. A control device according to claim 1, wherein one of the legs of said U-shaped supporting structure comprises an elongated angle member, and the other leg of said U-shaped structure comprises respective L-shaped members, disposed in aligned side-by-side relation with the leg portions thereof disposed in respective common planes, each of such L-shaped members having a leg portion disposed in opposed relation with respect to one leg of said angle member, and cooperable therewith to form the intermediate portion of said U-shaped structure, each of said resilient elements having the mounted end thereof extending transversely to the remainder thereof and clamped between said cooperable portions of said angle member and a respective L-shaped member, each such L-shaped member being individually secured by screw means to the angle member, whereby each resilient element may be

detached from the supporting structure independently of the remainder of said elements.

4. A control device according to claim 3, wherein 5 said L-shaped members form the lower leg of said support structure, with each of said L-shaped members having threaded therein the adjusting screw for the associated resilient element.

5. A control device according to claim 4, wherein 10 each of said screws is provided with a head at the opposite end thereof from the knob carried thereby, with such head disposed at the bottom side of the associated L-shaped member carrying the same, whereby the knob and screw assembly cannot be turned out of the associated L-shaped member.

15 6. A control device according to claim 5, comprising in further combination, mounting means for attaching the support structure to the water supply container for the water cylinder of such a press, said mounting means comprising a plurality of strips, longitudinally spaced 20 along said supporting structure with each strip secured at one end thereto, and at its opposite end to a cooperable block, each block having a notch therein of a size 25 to receive the adjacent edge of such a supply container, and having screw means adapted to clamp such an edge in said notch.

7. A control device according to claim 6, wherein 30 said mounting means includes a leg member carried by said support structure, of a length to rest upon the bottom wall of such a supply container, said leg member being threaded into and supported from a portion of the lower leg of said U-shaped support structure.

8. A control device according to claim 6, wherein 35 each resilient member is attached to the associated resilient element by detachable screw means, whereby the resilient member may be readily detached and replaced.
